UNITED STATES PATENT OFFICE.

LOUIS S. BURBANK, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

TENSION FOR SPOOLERS.

1,238,100.

Specification of Letters Patent. Patented Aug. 28, 1917.

Application filed February 23, 1916. Serial No. 79,866.

To all whom it may concern:

Be it known that I, LOUIS S. BURBANK, a citizen of the United States, and resident of Hopedale, county of Worcester, State of Massachusetts, have invented an Improvement in Tensions for Spoolers, of which the following description, in connection with the accompanying drawing, is a specification, like characters on the drawing representing like parts.

This invention relates to improvements in yarn winding machines in which the yarn wound is drawn substantially axially from a bobbin, cop or other yarn carrier. In such machines there is a considerable difference in the tension of the running strands which not only causes a lack of uniformity in winding upon the spools or other yarn receivers but also results in the wastage of a considerable amount of power where an unnecessary amount of tension is placed on the yarn running to a large number of spools.

One of the objects of the present invention is to provide a tension mechanism which may conveniently be regulated to provide for the uniform winding of the yarn and for the saving of the power which otherwise is wasted.

Another object of the invention is to provide means for preventing the formation of knots or kinks in the running strand between the spool and the yarn mass from which the spool is wound.

These objects are accomplished in the present invention by passing the yarn immediately after it leaves the yarn carrier over an adjustable rotatable tension device having a non-slipping surface.

Another object of the invention is to provide a tension device which may be quickly threaded by the operator.

Another object of the invention is to provide a tension device which will preserve the quality of the yarn by avoiding squeezing, and the consequent flattening, or scraping or otherwise roughening the surface of the yarn.

Another object of the present invention is to provide means for guiding the running strand properly to the tension device and for preventing the interference of adjacent strands by the ballooning caused by the rapid rotation of the yarn carrier.

Another feature of the invention consists

in providing means for preventing unskilled operators from tampering with the tension device.

Another feature of the invention consists in providing means for swinging the bobbin supporting spindles out of operative relation to their respective tension devices to facilitate the doffing and replacement of the bobbins.

Other objects of the invention and the nature thereof will more fully appear from the following description and the accompanying drawings and will be pointed out in the annexed claims.

The drawings illustrate a portion of a spooler with the present invention applied thereto.

In the drawings:

Figure 1 is a transverse sectional view of a sufficient portion of a spooler to illustrate the application of the present invention thereto,

Fig. 2 is a side elevation of a preferred embodiment of my invention.

Fig. 3 is a median sectional view of the tension device illustrated in Fig. 2 on line 3—3 Fig. 2, the rotatable tension member being shown in elevation, the device being shown in vertical position for convenience in reading.

Fig. 4 is a side elevation of the same, showing the friction member which controls the rotation of the rotatable tension cylinder in dotted lines, certain parts of the casting having been removed,

Fig. 5 is a view of a key for regulating the tension.

Fig. 6 is a vertical sectional view of a modified form of rotatable tension device of the class above described, and,

Fig. 7 is an end view thereof.

The yarn winding machine illustrated in the drawing may be a spooler of the usual type having a frame 1 supporting a series of spool carriers 2 upon which are mounted spools 3, the spool carriers being driven by whisks 4 through the medium of belts passing around a rotating drum 5.

The traverse of yarn upon the spools is effected through the usual thread guides 6 carried by a traverse rod 7, which is reciprocated by the rocker arms 8 which are oscillated through the yoke 9 in the usual manner.

The novel tension device forming the present invention consists of a rotatable member carried upon a stand 10 which preferably is provided with a flanged jaw 11 adapted to 5 embrace the rod 12 which extends longitudinally of the machine frame, said jaw being secured thereto by a set screw 13 passing through one member of the jaw and abutting against the rod 12.

10 The spindle 14 for supporting the bobbin preferably is secured to a bracket 15 by means of a set screw 16, the bracket 15 being pivotally mounted upon a stud or bolt 17 extending laterally from an extension 18 of 15 the lower end of the stand 10. The pivotal member 17 preferably is in the form of a screw headed bolt having a spring washer 19 interposed between the nuts 20 and the side of the extension 18.

20 The bracket 15 desirably is provided with divergent lugs 21, 22 sufficiently spaced apart that when the lug 21 is in engagement with the flange 11^x of the jaw 11 the axis of the spindle 14 will be substantially in alignment with the tension device and when the lug 22 is in engagement with the flange 11^x of the spindle 14 will be sufficiently out of alignment with the tension device to permit free removal of the bobbin or other yarn 25 carrier.

The frictional pivotal connection between the bracket 15 and the stand 10 will retain the spindle 14 either in operative or inoperative position when placed there by the 30 operator.

In order that the tension device may be located at approximately the same distance from the end of the bobbin or other yarn carrier, even though yarn carriers of different lengths are used, the stand 10 is provided with an adjustable extension 23 preferably connected to the stand by a bolt 24 passing through slots 25 in the stand 10 and extension 23. The extension 23 is provided 40 with a lateral extension or goose neck 26 upon which is mounted, or formed integral therewith, one of the members 27 of the casing which incloses the rotatable frictional member.

50 The member 27 preferably is substantially conoidal in form and if desired may be provided with a beak 27 to insure the guiding of the yarn and to prevent the interference of adjacent strands by ballooning. The 55 casing member 27 is provided at its smaller end with a preferably cylindrical recess 28, and the inner wall of the recess may, if desired, be machined to present a smooth surface 29 adapted to engage the end of the rotatable tension member 30, the recess 28 being of such a depth that the edge 31 of the casing member 27 will be in substantially the median transverse plane of the surface of the rotatable member.

65 The rotatable tension member 30 desirably

is provided with a hard non-slipping surface which will resist wear from the rapidly running thread and which may be knurled, striated or otherwise roughened to grip the yarn, but which preferably is a granular surface formed by coating a cylinder with carborundum, emery or other usual abrasive.

70 It is desirable that the rotatable tension member shall be constructed of material of light weight, such as wood, in order to eliminate as far as possible the momentum acquired by the rapid rotation of the member, so that its speed of revolution may be sensitively varied, that is, retarded or accelerated according to any requirements in the 75 operation of the machine such as in starting the device or by the sudden arrest of the tension member due to the kinking of the yarn, thus avoiding undue variations in tension upon the yarn which would be caused by the momentum of a relatively heavy rotatable tension member.

80 By having the rotatable tension member of relatively large diameter the tension imposed upon the yarn will not be affected by changes in the speed of the yarn caused by the building up of the winding upon the spool, consequently no compensating mechanism is required; furthermore the variation 85 in thickness, weight, or stiffness of the yarn will not materially affect the tension imposed upon it by a rotatable tension member of the character above described.

90 The rotatable tension member preferably 95 is made of a wood of such porosity that it is capable of absorbing oil freely so that the cylinder when soaked in oil may be run continuously without the necessity of further lubrication.

100 The cylindrical tension member 30 may conveniently be mounted upon a pin or stud 33 projecting axially from the casing member 27 and its freedom of revolution controlled by a friction disk 34 pressing against 105 the opposite end of the cylinder from that which rests against the machined surface 29. The pressure between the friction disk 34 and the end of the cylinder may conveniently be regulated by a nut 35 mounted 110 upon a left hand screw 36 upon the stud 33, a spring washer 37 desirably being interposed between said nut and the tension disk to permit a proper amount of slippage of the rotatable tension member to prevent 115 breaking the yarn. The spring washer 37 may, as illustrated in Fig. 4, be in the form of a hub 38 having laterally extending arms 39 engaging the friction disk 34.

120 The stud 33 preferably is provided with an end portion 40 of slightly smaller diameter than the screw threaded portion 36, thereby providing a seat for a complementary casing member 41 which may be conveniently secured thereupon by a nut 42. 125 130 135

The adjacent ends of the conoidal casing members 27 and 41 are spaced apart a short distance to provide a guideway for the yarn leading to the cylindrical tension member. 5 The complementary member 41 is provided with a cylindrical recess 43 adapted to inclose a portion of the tension member 30, the washer 34 and the adjusting nut 35. This casing is provided with a rib 44 adapted to engage a slot 45 in the friction disk 34 to prevent the same from rotation. The member 41 also is provided with a preferably cylindrical aperture 46 adapted to form a bearing for the shank 47 of the key, (see 15 Fig. 5) which conveniently may be made in the form of a cylinder having a knurled end gripping portion 48 and a toothed end 49 adapted to engage teeth 50 in the cylindrical periphery of the nut 35. It will be obvious 20 from the construction thus described that a skilled operator such as the foreman may be provided with a key by which he may adjust the pressure of the friction disks against the rotatable tension members to provide a uniform 25 form spooling tension throughout the entire yarn winding machine and having once set the tension device remain assured that unskilled operators will not tamper with the same.

30 The stands 10 may be adjusted upon the rods 12 so that the axis of the spindles 14 may be positioned at any desirable inclination, such as that illustrated in Fig. 1, and by reason of the adjustability of the extension 23 of the stand 10 the tension device may be placed at the desired distance from the ends of the yarn carriers whether the same be short or relatively long.

The axes of the spindles preferably are 40 tangential to the surface of the cylindrical tension member and in the operation of the machine the yarn is carried directly over the tension member, or preferably with one turn about the same, so that there is always a positive engagement between the yarn and the rotatable frictional member and a uniform tension thereby interposed upon the running strand, and led therefrom directly over the traverse rod 7, through the guide 45 6 to the spool or other yarn receiver. The conoidal surfaces of the casing members 27, 41 serve to direct the yarn, notwithstanding its ballooning, into the slot or space between the adjacent ends of said members.

55 It is found in practice that the roughened or granular surface of the rotatable tension member serves not only to maintain an even tension upon the yarn but also removes burs and imperfections from the yarn and by 60 reason of the rapidity of its rotation develops a sufficient centrifugal force to render the device self clearing, thereby avoiding the necessity of stopping the machine to remove the accumulation of lint, etc., in the 65 tension device.

In Figs. 6 and 7 a modified form of tension device is illustrated. In this device the goose neck 26 of the extension 23 is provided with a spherical socket 51 which receives a spherical head 52 extending centrally from the base 53 of the conoidal casing member 54, the member 54 being provided with a preferably conical recess the flat base 55 of which is adapted to engage frictionally the end of the rotatable tension member 57, the cylindrical surface of which is provided with a roughened or granular yarn engaging surface 58 of the character above described. Rotation of the casing member 54 may effectively be prevented by a lug or fin 26* upon the goose neck 26 engaging a suitable recess on the back of the casing.

The rotatable tension member 58 may conveniently be mounted upon a shaft 59 extending centrally through the spherical boss 51 of the casing and having a screw threaded portion 60 engaging screw threads 61 in an aperture extending through the goose neck 26.

A set nut 62, which may be in the form of a toothed or knurled wheel, may be provided to maintain the shaft 60 in adjusted position. The coöperating casing member 63 also is preferably conical in form complementary to the recess in the casing member 54 and the flat base 64 of said recess engages the opposite end of the rotatable tension member 58 to that engaged by the base 55 of the casing member 54. The casing member 63 desirably is provided with oppositely disposed inwardly extending ribs or lugs 66, 67 which form a seat for a spring 68 preferably in the form of a wire passing through an aperture 70 in the outer end of the shaft 59 so that the casing member 63 is retained in yielding frictional engagement with the end 65 of the rotatable member.

In order to adjust the tension in this device the set nut 62 is released and the conoidal casing member 63 rotated to screw up the frictional surface more tightly against the conoidal end of the rotatable member or it may be unscrewed to reduce the pressure thereagainst. When the desired pressure is 110 acquired the set nut 63 is screwed up tightly to maintain the parts in adjusted position. This tension device is positioned in the same manner as that illustrated in Figs. 2, 3 and 4 and is adapted to operate in the same way.

115 While the rotatable tension device is illustrated herein as cylindrical in form it will be readily understood that other forms of rotatable tension members may be utilized within the spirit and scope of the accompanying claims and that various other forms of adjustment therefor may be used.

120 It will also be understood that the features of construction disclosed herein are 125 illustrative merely and that various other forms of adjustment therefor may be used.

130

ifications may be made within the spirit and scope of the following claims.

Having thus described my invention what I claim as new and desire to secure by Letters Patent is:

1. In a winding machine in which the yarn is wound from a yarn carrier upon the rotating yarn receiver, a rotatable tension member located in proximity to the end 10 of said yarn carrier engaging the running strand and rotated thereby, and means for adjusting the rotating tension member toward and from the end of the yarn carrier in the direction of the axis of said yarn carrier whereby said tension member will be properly located in respect to the ends of 15 yarn carriers of different lengths.
2. In a yarn winding machine a tension device comprising a rotatable cylindrical member having a non-slipping yarn engaging surface, narrowly separated casing members surrounding said rotatable tension member having oppositely inclined surfaces for guiding the strand into position upon 20 said cylindrical member and means frictionally engaging the ends of said member inclosed within said casing members.
3. In a yarn winding machine a tension device comprising a rotatable cylindrical member constructed of a porous material 25 impregnated with a lubricant and having a non-slipping thread engaging surface, means for guiding the running strand thereupon and means frictionally engaging said member to control the rotation thereof.
4. In a yarn winding machine, a tension device comprising a rotatable cylindrical member constructed of wood soaked in a lubricant and having its cylindrical surface 30 coated with a granular substance, means for guiding the running strand thereupon and means frictionally engaging said rotatable member.
5. A tension device for a running strand 45 of yarn comprising two oppositely disposed conical members having recesses in adjacent ends and spaced apart to form a guideway for the running strand, a cylindrical tension member rotatably mounted within said 50 recess having one end engaging one of said members, a frictional instrumentality carried by the other stationary member engaging the opposite end of said rotatable member, and means for adjusting said frictional instrumentality.
6. A tension device for a running strand 60 of yarn comprising two oppositely disposed conical members having recesses in adjacent ends and spaced apart to form a guideway for the running strand, a cylindrical yarn 65 engaging member mounted within said recess upon a shaft connecting said conical members and having one end engaging one of said members, a friction disk engaging

the opposite end of said rotatable member, a spring engaging said disk, and means for adjusting the pressure upon said spring.

7. A tension device for a running strand of yarn comprising two oppositely disposed conical members having recesses in adjacent 70 ends and spaced apart to form a guideway for the running strand, a cylindrical yarn guiding member rotatably mounted within said recess upon a shaft connecting said conical members and having one end engaging one of said members, a friction disk engaging the opposite end of said rotatable member, a spring engaging said disk and means for adjusting the pressure upon said spring comprising a nut having a toothed 75 periphery mounted upon said shaft, and a bearing in one of said conical members adapted to receive a key for rotating said nut.

8. A tension device for a running strand 85 of yarn comprising a rotatable tension member adapted to engage the yarn and be rotated thereby, a casing substantially inclosing said rotating member, means frictionally engaging said rotating member and means 90 operable by a key inserted through an aperture in said casing for adjusting the pressure of said frictional engaging means upon said rotatable member.

9. A tension device for a rotating strand 95 comprising a tension member rotatably mounted upon a shaft within a substantially closed casing and adapted to be engaged and rotated by the running strand, means frictionally engaging said rotatable member, a 100 nut screw threaded upon said shaft and adapted to be rotated to regulate the pressure upon said frictional means, said nut being provided with a toothed cylindrical periphery, adapted to be rotated by a key 105 complementary teeth.

10. In a yarn winding machine a stand having a lateral extension supporting a tension device connected to the side rail of the machine, a spindle supporting bracket pivotally connected to said stand and adapted to be adjusted to position the axis of the spindle in substantial alinement with the tension device or to be swung from said position to facilitate the dosing of the yarn carrier 110 and means for adjusting the position of said tension device in the direction of the axis of said spindles.

11. In a yarn winding machine a stand connected to the side rail of the machine 120 and provided with an arm formed of two relatively adjustable sections, a rotatable tension device upon the end section, a spindle supporting bracket pivotally connected to said stand and adapted to be adjusted to 125 position the axis of the spindle in substantial alinement with the tension device or to be swung from said position to facilitate

the doffing of the yarn carrier, frictional means for retaining said spindle supporting bracket in adjusted positions, and means for limiting the extent of said swinging movement.

12. In a yarn winding machine a stand having a lateral extension supporting a tension device connected to the side rail of the machine, a spindle supporting bracket pivotally connected to said stand and adapted to be adjusted to position the axis of the spindle in substantial alinement with the tension device or to be swung from said position to facilitate the doffing of the yarn carrier, frictional means for retaining said spindle supporting bracket in adjusted positions, and means for limiting the extent of said swinging movement, consisting of two interengaging extensions upon said stand and bracket adapted to permit a predetermined limited relative movement.

13. In a yarn winding machine a stand having a lateral extension supporting a tension device, connected to the side rail of the machine, a spindle supporting bracket pivotally connected to said stand and adapted to be adjusted to position the axis of the spindle in substantial alinement with the tension device or to be swung from said position to facilitate the doffing of the yarn carrier, frictional means for retaining said spindle supporting bracket in adjusted positions, and means for limiting the extent of said swinging movement, consisting of a pair of divergent projections on said bracket embracing a relatively stationary projection on said stand and spaced apart sufficiently to permit a predetermined relative movement therebetween.

In testimony whereof, I have signed my name to this specification.

LOUIS S. BURBANK.
